UNITED STATES PATENT OFFICE.

ERWIN WESNICK, OF BERLIN, GERMANY.

ADJUSTABLE OR SELF-REGULATING PROPELLER.

1,425,922.

Specification of Letters Patent. Patented Aug. 15, 1922.

Application filed June 29, 1920. Serial No. 392,534.

(GRANTED UNDER THE PROVISIONS OF THE ACT OF MARCH 3, 1921, 41 STAT. L., 1313.)

To all whom it may concern:

Be it known that I, ERWIN WESNICK, a citizen of Germany, and a resident of Berlin, Germany, have invented certain new and useful Improvements in Adjustable or Self-Regulating Propellers, of which the following is a specification, and for which patents have been granted in Germany, Nos. 326213, filed 20th April, 1918, and 327778, filed 27th 10 August, 1918, in the name of my assignees, the Helix Propeller Gesellschaft, Berlin, Germany, Blucherstrasse No. 1; and I do hereby declare the following to be a full, clear, and exact description of the invention, 15 such as will enable others skilled in the art to which it appertains to make and use the same, reference being had to the accompanying drawings, and to the letters or figures of reference marked thereon, which form a 20 part of this specification.

The invention relates to improvements in adjusting devices of propeller blades, especially for air service. Commonly the adjustment movements are effected from some 25 part of the machine rigidly connected to the foundation of same; the movement being transmitted to the blades of the rotating screw propeller by axially displacing a sleeve on the propeller axis or by using an 30 arrangement of toothed gear wheels for example in the form of a differential gear or planet gear as used in automobile practice. In most of such cases difficulties arise because there is not enough space available 35 between the hub of the propeller and the bearing of the propeller shaft for receiving the device, whilst the accommodation of the adjusting device in the interior of a hollow propeller shaft is only possible in connection 40 with the use of an intermediate gear between the motor and a propeller shaft freely accessible from its end opposite to the propeller.

The invention consists in using as foundation 45 for the parts exerting the adjusting forces not a rigid part of the machine frame but the air, by providing at the propeller an arrangement of two or more auxiliary blades constructed to act as an air turbine or as braking blades and connected to any propeller blade adjusting device mounted 50 in the axis of the propeller in such a manner that the said arrangement is adapted to drive the adjusting device with a greater or

smaller number of revolutions than the 55 number of revolutions of the propeller shaft. Thereby the propeller blades are rotated at their respective shafts in the one or the other direction so as to increase or to diminish the pitch of the propeller blades. 60

The advantage of this arrangement consists therein, that no transmission means are needed for transmitting the considerable adjusting forces from a stationary part to the rotating propeller, these forces being 65 generated immediately in the auxiliary arrangement or air servomotor mounted at the rotating parts of the propeller.

A further feature of the invention consists in the regulation of the air servomotor 70 by a centrifugal regulator rotating with the propeller and connected to the gear of the air servomotor, so as to put it into action in the case the number of revolutions of the propeller shaft is too great or too 75 small, for the purpose of increasing or diminishing the pitch of the propeller and the force needed for the rotation of said propeller; thereby it is attained that the number of revolutions of the propeller remains 80 substantially the same at the various conditions of flight, may it be in great altitude or near the ground, and may the aeroplane driven by the propeller be in ascending or descending state. For this purpose a 85 member influenced by the air pressure may be provided in addition to or in place of a centrifugal regulator.

The invention further relates to several 90 improvements in the details of construction of the air servomotor, the regulator, the means for reversing the propeller blades, and the accommodation of the rotatable blades as hereafter described.

The invention is illustrated in the accompanying drawing, in which

Figs. 1, 2 and 3 are a longitudinal section, a frontal view and an upper view, partly in section, of one form of construction of the propeller.

Fig. 4 is a frontal view of the hub portion.

Figs. 5, 6 and 7 are a side view, partly in section, a frontal view and an upper view of a second form of the propeller

a third form of construction, in which the auxiliary blades are fastened to a cap including the hub of the propeller, and a gyroscopic device is mounted in said cap.

5 At the first form of construction (Figs. 1-4) the hub 1 is a flat part, at one side of which in the direction of the motor shaft mounted transversely in the hub is attached a sleeve 2, in the interior of which may be 10 placed the nut fastening the propeller hub at the motor shaft, and its accessories. The hub 1 is constructed in one piece with two parallel planes 3 on which the propeller blades abut. The centrifugal forces of the 15 blades are sustained by bolts 4 which are surrounded between the planes 3 by stiffening tubes 5 and extend beyond the planes 3 through distance tubes 6 and to annular bodies 7. In these annular bodies 7 ball 20 bearings 8 are enclosed by which are surrounded and sustained iron blade sleeves 9. The said blade sleeves 9 are centrally guided at the hub planes 3 by circular guide faces and support the blades 10 which are inserted 25 in them with cylindrical base parts.

The insertion of the wooden blades 10 in the sleeves 9 is effected as follows. The base parts of the blade are primarily armoured with a ring 11 shrunk on each base part for 30 the purpose of obviating destruction by splitting the wood; then the base parts are turned cylindrically and milled in the interior to get the annular slot 12 (or several such slots in concentric arrangement) and a central bore 13. Thereupon wedge shaped bodies 14, 15 are inserted the inmost of which is secured by a screw 16 screwed into the wood. The annular wedge 15 is extending in form of ribs 17 into the radial slots 40 of the wood splitted by driving in the wedges. In this state the blade base is turned to a shape corresponding to the interior shape of the blade sleeve 9. Thereupon the wedges 14, 15 are drawn out, the 45 blade base is inserted into the sleeve 9 and the wedges are again inserted and secured by the screw 16.

For the purpose of adjusting or rotating the blades there are provided conical toothed 50 gear wheel segments 18 at the sleeves 9, and the said segments 18 are meshing with a conical toothed gear wheel 19 rotatably mounted at the above mentioned hub sleeve 2. The conical wheel 19 is connected by a 55 tube or sleeve to the hub 20 of a little adjustable auxiliary propeller serving as a servomotor. The auxiliary propeller hub 20 for this purpose is fitted with two screw bolts 21 on which are screwed the auxiliary 60 blades 22 by aid of bearing nuts 23, conically inserted into the blades. Sleeves 24 are shrunk on the base parts of the wooden auxiliary blades and said sleeves 24 are provided with teeth, with which are meshing toothed rods 25 of a slide 26, which said

slide, by the aid of a thrust bearing 27 constructed as a ball bearing, is connected to a regulator sleeve 28. The regulator consists in two flat springs 29 attached at one end to two of the above mentioned bolts 4 respectively and at the other end to the regulator sleeve 28 and provided in their middle parts with centrifugal blocks 30.

The operation is as follows. When the propeller is in rotation the centrifugal blocks 30 assume a certain medium position under the influences of the centrifugal force and the springs 29. The regulator sleeve 28 at this position of the parts is advanced as far as to hold by the toothed rods 25 the auxiliary blades in a medium position adapted to cause the auxiliary propeller to revolve under the influence of the air current generated by the main blades 10 with the same number of revolutions as the main 85 propeller. Thereby no relative displacement is caused between the rotating parts and the propeller is uniformly running. If for some reasons the propeller assumes a too fast rotation the sleeve 28 is approached by the 90 regulator to the hub portion 1, 3 and the auxiliary blades are thereby adjusted to assume a greater pitch with the result that the auxiliary propeller revolves less fast than the main propeller, and the relative displacement between the auxiliary propeller hub 20 and the gear wheel 19 connected thereto effects that by the aid of the toothed segments 18 the blades 10 are adjusted to assume a greater pitch; the propeller then consumes a greater amount of force, so that the motor is running more slowly and gets again its normal number of revolutions. If in the reverse case the motor begins to run too slowly, all motions are caused in the inverse sense, with the result that again the normal number of revolutions is reached, provided that the motor is in good working order.

Referring now to the second form of construction (Figs. 5-8) the hub parts 1 to 17 are constructed in the same manner as at the above described form, and are indicated by the same reference numerals.

The blade sleeves 9 are here fitted with worm wheels 31 meshing with worms 32, the shafts 33 of which are provided with a toothed wheel 34 each. The said toothed wheels may be replaced by frictional wheels and are meshing with a central wheel 35 115 rotatably mounted on the sleeve 2. The central gear wheel 35 is driven by a second central wheel 36 provided with two flat 120 braking blades 37, in the following manner. A transmitting gear wheel 38, and two further transmitting gear wheels 39, 40 meshing with each other, are mounted at a slide 41 in such a manner that at one end position of said slide the one transmitting wheel 38 meshes with the two central wheels 35, 125 130

36 thereby causing them to move in the same direction; at the reverse movement of said slide of the transmitting wheels 39, 40 the one is meshing with the one central wheel 5 36 and the other with the other central wheel 35, thereby causing the central wheels to revolve in reverse directions.

The said slide 41 is slidably mounted at a guide plate 42 of the hub sleeve 2 and is 10 moved by a centrifugal regulator to and fro between its end positions. The regulator comprises a sleeve or collar 43 to which are linked centrifugal blocks 44 provided each with a tooth 45 engaging the sleeve 2 in 15 such a manner that the blocks 44 at moving about their links cause the collar 43 to rotate about the sleeve 2. A pin 46 extending from the collar 43 into a slotted portion 47 of the slide serves to transform 20 the rotating movements of the collar 43 into the above mentioned longitudinal sliding movements of the slide 41, and to bring thereby into engagement with the central wheels 35, 36 the transmitting wheels 38, 5 or 39, 40 respectively, or to hold said wheels out of engagement.

The force driving the regulator blocks 44 towards the axis of the propeller is furnished by a spiral spring 44', the one end of which is attached to the collar 43, and the other end to a collar 45' rigidly connected to the sleeve 2. The said collar 45', instead of being rigidly connected to the sleeve 2, may be mounted thereon rotatably 25 and may be influenced by a gear so as to be rotated at the will of the operator, in order to change the tension of the spiral spring 44' and thereby change the normal number of revolutions to be assumed by the motor and propeller.

The operation of this form of execution is as follows. If the motor is running with normal speed the transmitting wheels 38 and 39, 40 are not in engagement with the central wheels 35, 36, and the auxiliary blades 37 as well as the wheel 36 rest without any substantial rotation, whilst the wheel 35 is 45 rotated synchronously with the propeller without influencing in any way the blades 50 10, the latter being held in position by the automatic blocking effectiveness of the worm gears 31, 32. If the number of revolutions of the propeller grows too great or too small, the centrifugal blocks 44 are swung 55 out of their medium position into one or the other direction, and thereby the collar 43 is rotated in the respective direction, so as to move the slide 41 in the respective direction and to get the transmitting wheels 38 or 39, 40 respectively into engagement 60 with the central wheels 35, 36. The auxiliary blade 37 thereby is coupled to the adjustment gear so as to be rotated with a certain speed in equal sense with the propeller but exert a rotating force upon the

adjusting gear in the one or the other sense and thereby adjusting the blades 10 in the manner described at the first form of execution.

The operation of the above mentioned adjusting device of the regulator spring 44' is the following. If for instance the operator releases the tension of the said spring the centrifugal blocks 44 will overcome the force of the spring in the same manner as 70 if the propeller were running too fast. The auxiliary blade arrangement is thereby caused to increase the pitch of the main blades 10, and a smaller number of revolutions is attained. If the operator does still 75 more release the tension of the spring, there is coming a point in which the pitch of the blades is the greatest possible, and a further shifting of the blades in the same direction effects a reverse thrust of the propeller; provided that the motor is sufficiently powerful to run under these conditions, is obtained in 80 this manner the reversibility of the propeller. The method of again adjusting the propeller to the prior state then consists in 85 again giving the regulator spring a stronger tension, whereupon all movements will proceed in the inverse direction and normal working of the propeller will be obtained.

The dimensions of the auxiliary blade 37 90 95 may be chosen without difficulty so as to exert a sufficient adjusting force for quickly adjusting the blades 10, whilst on the other hand the force exerted should be sufficiently great only at a relatively great speed of the auxiliary blade in order to avoid a too hard engagement of the gear wheels.

Referring to the third form of construction (Fig. 9) the essential features of the propeller and the gear correspond to those 100 of the second form of execution, with the exception that instead of the auxiliary blade 37 at the hub of the central wheel 36 there is arranged a sheet metal cap 49 shaped like the usual propeller caps and provided 110 with a removable cover 50 in its fore part, and completed at its back portion by a ring 51 held by struts 52 mounted at the rigid parts of the propeller hub.

The rotatable cap 49 is provided at its 115 outer surface with four or six sheet metal ribs 53 which act as braking blades, i. e. cause the cap to stand still or to rotate only more slowly than the propeller. Thereby the same effect is attained as at the second 120 form of execution of the auxiliary blades.

The ribs 53 may be arranged partly in the form of screws with a pitch ascending in the sense of the revolution of a watch hand and partly in the form of screws with 125 reverse pitch. By alternately laying flat, or pulling into the interior of the cap, the one or the other set of the said ribs may be got out of action, so as to perform the same mode of action as described in connection with the 130

adjustable auxiliary blades 22 of the first named form of execution as above mentioned.

In the third form of execution are furthermore arranged in a cap 49 two gyroscopes 5 54 provided with conical gear wheels 55 meshing with a gear wheel 56 fitted to the hub of the propeller. As the cap is resting without rotation, or at least is rotated less quickly than the propeller, the gyroscopes 10 54 are rotated by means of the gear 55, 56 and assist the resisting force of the cap 49 against being rotated, so as to augment the adjusting force available. If needed all the accessories known in connection with ships' 15 gyroscopes may be provided and the gyroscopes may be driven by electrical force. Under certain conditions the ribs 53 may be avoided, the cap being arrested against rotation only by the gyroscopes. The respective 20 axis of the propeller blades may be arranged with a pronation and with an eccentric position in relation to the propeller shaft axis in order to diminish the stresses exerted on the shifting bearings of 25 the blades 10 in a known manner without interfering with the invention.

Having now particularly described my invention, what I claim as new and desire to secure by Letters Patent of the United 30 States is:

1. In screw propellers the combination with propeller blades rotatably mounted at a hub, of an auxiliary blade rotatably mounted at the said hub and means for transmitting the rotating movements of said auxiliary blade onto the rotatably mounted propeller blades.
2. In screw propellers the combination with propeller blades rotatably mounted at a hub, of an auxiliary screw propeller blade 40 rotatably mounted at the said hub and adapted to be adjusted to various screw pitches and means for transmitting the rotating movements of said auxiliary blade onto the rotatably mounted propeller blades.
3. In screw propellers the combination with propeller blades rotatably mounted at a hub, of auxiliary blades mounted at said hub and only acting as braking blades and means for transmitting the rotating movements of said braking blades onto the rotatably mounted propeller blades.
4. In screw propellers the combination with propeller blades rotatably mounted at a hub, of auxiliary blades mounted at the 50 said hub and only acting as braking blades,

means for transmitting the rotating movements of said braking blades onto the rotatably mounted propeller blades, and means for changing the sense of rotation of 60 the propeller blades in relation to the sense of rotation of the auxiliary blade arrangement.

5. In screw propellers the combination with propeller blades rotatably mounted at a hub, an auxiliary blade device rotatably mounted at said hub and means for transmitting the rotating movements of said auxiliary blade device onto the propeller blades, of a regulating device adapted to 70 automatically change the pitch of said auxiliary blade device or the gearing connecting the said rotatable auxiliary blade device to the rotatably mounted propeller blades.

6. In screw propellers the combination with propeller blades rotatably mounted at a hub, an auxiliary blade device rotatably mounted at said hub and means for transmitting the rotating movement of said auxiliary blade device onto the propeller blades, and a regulating device adapted to automatically adjust the propeller blades by the aid of said auxiliary blade device, of a spring balancing the force of the regulator, 85 and means for adjusting the tension of the said spring by the hand of the operator.

7. In screw propellers the combination with propeller blades rotatably mounted at a hub, of an auxiliary blade device rotatably mounted at the said hub and means for transmitting the rotating movements of said auxiliary blade device onto the rotatably mounted propeller blades, of a cap enclosing the said means and provided at its 90 outer surface with ribs adapted to act as the said auxiliary blade.

8. In screw propellers the combination with propeller blades rotatably mounted at a hub, of one or more gyroscopes mounted at a body rotatably attached to the said hub, means for driving the said gyroscopes, and means for transmitting the rotating movements of the said body onto the rotatably mounted propeller blades.

In testimony that I claim the foregoing as my invention I have signed my name in presence of two subscribing witnesses.

ERWIN WESNIGK.
